ROCKER SIDE BEARING

Jesse F. Holloway, Aldan, Pa.

Application August 25, 1934, Serial No. 741,359

6 Claims. (Cl. 308—224)

This invention relates generally to railway trucks and more particularly to improved rocker side bearings.

One object of my invention is to provide an improved rocker side bearing having bearing pockets on each side of a center plate to receive a pair of improved coacting gravity aligning rockers which carry the entire weight of the spring portion load of the railway vehicle whether it is an electric locomotive or a passenger car or freight car.

A further and more specific object of the invention is to provide a pair of improved cooperating gravity aligning side bearing rockers so constructed and arranged that said rockers are always biased toward self-contained counteracting relation, thereby causing the rockers to maintain their normal relation at all times even though the weight is temporarily lifted from the rockers such as when the railway vehicle travels around a curve or is otherwise caused to sway temporarily by centrifugal action.

Other objects and advantages will be more apparent to those skilled in the art from the following description of the accompanying drawing in which:

Fig. 1 is a fragmentary vertical transverse section of a vehicle frame and the bolster and center pin arrangement;

Fig. 2 is a vertical longitudinal section taken on the line 2—2 of Fig. 1;

Fig. 3 is a perspective of one of the cooperating rockers;

Fig. 4 is a perspective of the top of the liner for the rockers;

Fig. 5 is a perspective of the lower liner for the rockers.

In the illustrated embodiment of my invention which is shown herein merely for the purpose of disclosing one specific form among possible others that the invention might take in practice, I have applied the invention to a center pin construction of the type disclosed in the joint patent of Harry Glaenzer and Allen Wallace, Patent Number 2,038,560, issued April 28, 1936, although it will of course be understood that the invention is applicable to other types of center pin constructions. A locomotive frame generally indicated at 1 has a center pin 2 projecting downwardly for engagement with a truck bolster 3, it being noted that a housing 4 extends upwardly from the bolster to provide not only an ample axial bearing for center pin 2 but also to support an equalizing spring carriage 5. The truck bolster as is usual is adapted to swing about the center pin 2. Other

usual truck and bolster elements have been omitted for the sake of clearness, although it will of course be understood that such elements would be associated with the truck and bolster. The outer ends of the equalizing spring carriage 5 support the spring rigging including springs 6, the spring rigging being suitably attached to the locomotive frame 1. The weight is thus transmitted through spring 6 to the equalizing spring carriage 5 and thence transmitted to the bolster 10 5 through my improved rocker side bearings generally indicated at 7. The weight of frame 1 is not in any way transmitted through the center pin 2, this pin merely serving a centering function. The pin permits relative vertical movement 15 between the truck bolster 3 and spring carriage 5.

The side rocker bearings are identical and hence the description of one will suffice for both. As shown in Fig. 2, the spring carriage is provided with a suitable recess 8 having lateral openings 9, the truck bolster also being provided with a suitable bearing recess 10. A top liner 11 is welded or otherwise suitably secured to the spring carriage, and this liner as shown in Figs. 2 and 4 has down-turned ends 12. A bottom liner 13 is 20 25 inserted in recess 10. A pair of cooperating self-centering rockers 14 and 15 is interposed between the liners 11 and 13.

The two rockers are identical, and hence the description of one will suffice for both. As 30 shown in Fig. 3, the rocker comprises a center portion 16 and upper and lower lateral portions 17 on the outside and upper and lower lateral portions 18 on the inside. The portions 18 project laterally to a greater extent and with a greater 35 amount of weight than the lateral portion 17, thus creating a preponderance of weight on the inner side with respect to the center 19 about which the radii of the two bearing surfaces 20 and 21 are struck. While these radii are thus identical 40 and struck from the same center, it will of course be understood that the bearing surfaces 20 and 21 may have any desired curvature. The inner faces 23 of the lateral portions 18 constitute coacting or aligning surfaces for the rockers when 45 positioned between the bearing liners 11 and 13 shown in Fig. 2. These inner faces are of sufficient height to prevent locking one with the other at the extreme limits of travel of the rockers such as when the locomotive or car is negotiating curves. 50

In operation, the rockers 16 are normally disposed as shown in Fig. 2, that is, with the mutual aligning surfaces 23 in contact, or substantially so, with each other about a vertical plane. The 55

outermost corners of the lateral portions 17 will be relatively close to the down-turned edges 12 of the upper liner 11 and to the side walls of the bolster recess 10. Assuming now that the railway vehicle is travelling around a curve, then bolster 3 rotates about center pin 2, thus causing rockers 16 to rock about their curved bearing surfaces 20 and 21. The longitudinal axes of these rockers are then inclined but remain parallel to each other, and the aligning surfaces 23 maintain contact with each other. As the vehicle comes on to the straight portion of the track, the truck bolster rotates to its normal position, and the rockers assume the position shown in Fig. 2. If for any reason, one side of the spring carriage 5 should lift, ever so slightly, upwardly away from the truck bolster so as to momentarily relieve the weight on rockers 16, still these rockers will be maintained in their normal contacting relation along faces 23 due to the preponderance of overlying weight in the lateral portions 18 tending to swing each of the rockers inwardly toward each other. Hence when the weight of the car is again applied to the rockers, they will be in their normal relation to transmit the full load. If the weight should be momentarily lifted from the rockers while travelling around a curve, at which time the rockers are inclined away from the vertical, still the rockers are maintained in contacting relation with each other without any possibility of swinging back to a vertical plane, this being due to the down-turned edges 12 or the walls of recess 10 engaging the upper outer corners of lateral portion 17. During this or other times, the aligning faces may separate, but this would be only slightly and would not prevent the weighted portions 18 from functioning to restore or maintain the rockers in parallel relation.

From the foregoing disclosure it is seen that I have provided an extremely simple and yet highly effective rocker bearing to carry and transmit the weight to the truck bolster and at the same time insure proper relation between the cooperating rockers irrespective of whether the railway vehicle is travelling around a curve or on a straight track or whether the weight is momentarily lifted from one or the other of the two sets of rockers during either of the foregoing directions of travel. It is also seen that the rockers are easily formed to insure their gravity self-alignment and that while each of the rockers might be termed broadly as having an eccentrically weighted I-section construction and that the rockers are identical, yet the rockers might take various other forms broadly involving the gravity aligning principle herein disclosed together with other features as set forth.

It will of course be understood that various

changes in details of construction and arrangement of parts may be made by those skilled in the art without departing from the spirit of the invention as set forth in the appended claims.

5

I claim:

1. A side bearing for railway vehicles comprising, in combination, a pair of opposed seats, and a pair of rockers interposed between said seats and having coacting surfaces and eccentrically weighted portions for biasing said rockers into said coacting engagement, said coacting surfaces being formed on said eccentric portions.
2. A side bearing for railway vehicles comprising, in combination, a pair of opposed seats, and a pair of substantially identical rockers interposed between said seats and having mutually aligning coacting surfaces and eccentrically weighted portions for biasing said rockers into coacting engagement with each other, said coacting surfaces being formed on said eccentric portions.
3. A side bearing for railway vehicles comprising, in combination, a pair of opposed seats, and a pair of substantially identical rockers interposed between said seats and having mutually aligning coacting surfaces and eccentrically weighted portions for biasing said rockers into coacting engagement with each other, said coacting surfaces being formed on said eccentric portions, said rockers having upper and lower curved surfaces of substantially the same radii and engaging said seats.
4. A side bearing for railway vehicles comprising, in combination, a pair of opposed seats, and a pair of substantially identical rockers interposed between said seats and having mutually aligning coacting surfaces and eccentrically weighted portions for biasing said rockers into coacting engagement with each other, said coacting surfaces being formed on said eccentric portions, said rockers having upper and lower surfaces of substantially the same radii about the same center and engaging said seats.
5. A side bearing for railway vehicles comprising, in combination, a pair of opposed seats, and a pair of cooperating rockers interposed between said seats, one of said rockers being substantially an I-section with one of its inner flanges eccentrically weighted.
6. A side bearing for railway vehicles comprising, in combination, a pair of opposed seats, and a pair of cooperating rockers interposed between said seats, said rockers being of substantially I-section and having eccentrically weighted portions on the sides adjacent each other whereby their upper ends gravitate toward each other.

JESSE F. HOLLOWAY.
